UNITED STATES PATENT OFFICE.

ABRAHAM HURWITZ, OF NEW YORK, N. Y., ASSIGNOR TO LOUIS ROSENBERG, OF NEW YORK, N. Y.

DESIGN FOR A SCARF-PIN CLUTCH.

49,612.

Specification for Design.

Patented Sept. 5, 1916.

Application filed May 17, 1916. Serial No. 98,228. Term of patent 14 years.

To all whom it may concern:

Be it known that I, ABRAHAM HURWITZ, a citizen of the United States, and a resident of the borough of Manhattan, in the city, county, and State of New York, have invented a new, original, and ornamental Design for a Scarf-Pin Clutch, of which the following is a specification, reference being had to the accompanying drawing, forming part thereof.

Figure 1 is a face view of the clutch illustrating my new design; and Fig. 2 is a side view thereof.

I claim:

The ornamental design for a scarf pin clutch, as shown.

ABRAHAM HURWITZ.
